(57) **ABSTRACT**

There is provided a liquid supply device including: first and second valves; a head; a suction mechanism; and a controller. The controller is configured to: execute a valve-opening operation of opening the first and second valves, in response to a suction instruction; execute a valve-closing operation of closing the first valve depending on output of a first signal, and closing the second valve depending on output of a second signal, the first signal indicating that an amount of a first liquid in a first tank is a first threshold value or more, the second signal indicating that an amount of a second liquid in a second tank is a second threshold value or more; and execute a suction operation of driving the suction mechanism for a predetermined time period.

**LIQUID SUPPLY DEVICE, METHOD OF
SUPPLYING LIQUID, AND IMAGE
RECORDING DEVICE**

REFERENCE TO RELATED APPLICATIONS

This application claims priority from Japanese Patent Application No. 2021-177150 filed on Oct. 29, 2021. The entire content of the priority application is incorporated herein by reference.

BACKGROUND ART

There is known an image recording device comprising a head and a carriage mounted with the head, that discharges ink from nozzles of the head when the carriage moves in a predetermined direction. The image recording device has an ink supply device that supplies ink to the head from a reservoir of the ink. In the case of a plurality of kinds of inks is supplied, the ink supply device has a plurality of ink channels provided between a plurality of the reservoirs and the head.

There is a printer comprising: a head having four kinds of nozzles respectively discharging four colors of inks; and a cap collectively covering the four kinds of nozzles. In this printer, the four colors of inks are respectively supplied to four sub-tanks from four cartridges, and four ink channels are employed to respectively supply the four colors of inks to the head from the four sub-tanks.

DESCRIPTION

In the printer described in Japanese Patent Publication Laid Open No. 2020-011485, there is performed a so-called initial introduction where the four colors of inks are respectively initially introduced into the four ink channels by a suction pressure being applied from the head side. In this printer, ink is supplied employing a water head difference between the cartridge and the sub-tank. Therefore, as much ink will flow into the sub-tank from the cartridge as an amount of ink in the sub-tank that has flowed to the head side due to the suction pressure.

Sometimes, there is a difference in resistance between the four ink channels connecting the four sub-tanks and the head. In such a case, when the previously-mentioned initial introduction is performed, an amount of ink flowing to the head side from the sub-tank through a channel having a small channel resistance will increase, and an amount of ink flowing to the head side from the sub-tank through a channel having a large channel resistance will decrease. There will thus occur a difference in ink introduction amounts between the plurality of ink channels. This will result in that when, for example, suction time is set so that a sufficient amount of ink will flow to the head side through the channel having a large channel resistance, an excessive amount of ink will flow to the head side through the channel having a small channel resistance.

The present disclosure, which was made in view of the above-described circumstances, has an object of providing a means by which difference in liquid amounts flowing into a head through a plurality of channels by suction becomes smaller.

(1) A liquid supply device according to an aspect of the present disclosure includes: a first reservoir configured to store a first liquid;

a second reservoir configured to store a second liquid;

2

a first tank having flexibility, the first tank being positioned lower than the first reservoir; a second tank having a flexibility, the second tank being positioned lower than the second reservoir; a first valve configured to open and close a channel connecting the first reservoir and the first tank; a second valve configured to open and close a channel connecting the second reservoir and the second tank; a head, the first liquid being capable of flowing into the head from the first tank through a first channel, the second liquid being capable of flowing into the head from the second tank through a second channel; a suction mechanism configured to drive so that a suction pressure is applied to the first channel and the second channel from a head side, of the first channel and the second channel, at which the head is positioned; a first sensor; a second sensor; and a controller.

The controller is configured to: execute a valve-opening operation of opening the first valve and the second valve, in response to receiving of a suction instruction;

execute, after executing the valve-opening operation, a valve-closing operation of closing the first valve depending on output of a first signal from the first sensor, and closing the second valve depending on output of a second signal from the second sensor, the first signal being a signal indicating that an amount of the first liquid in the first tank is a first threshold value or more, the second signal being a signal indicating that an amount of the second liquid in the second tank is a second threshold value or more; and

execute, after executing the valve-closing operation, a suction operation of driving the suction mechanism for a predetermined time period.

According to the liquid supply device described above, in the liquid supply device configured to perform suction to introduce the liquid into the plurality of channels connecting the plurality of reservoirs and the head, the suction mechanism is driven in a state where the liquid of not less than the predetermined amount has been supplied to each of the tanks, and supply of the liquid to each of the tanks from each of the reservoirs then has been stopped. Therefore, difference in liquid amounts flowing into the head through the plurality of channels by suction becomes smaller.

(2) According to another aspect of the present disclosure, the controller may be configured to execute, after executing the suction operation, the valve-opening operation again.

(3) According to another aspect of the present disclosure, the controller may be configured to open the first valve depending on output of a third signal from the first sensor, and open the second valve depending on output of a fourth signal from the second sensor, the third signal being a signal indicating that the amount of the first liquid in the first tank is less than a third threshold value smaller than the first threshold value, the fourth signal being a signal indicating that the amount of the second liquid in the second tank is less than a fourth threshold value smaller than the second threshold value.

(4) According to another aspect of the present disclosure, the first sensor may include a first signal outputting sensor configured to output the first signal and a third signal outputting sensor configured to output the third signal, and the second sensor may include a second signal outputting

sensor configured to output the second signal and a fourth signal outputting sensor configured to output the fourth signal.

(5) According to another aspect of the present disclosure, the controller may be configured to repeatedly execute the valve-opening operation, the valve-closing operation, and the suction operation a predetermined number of times, in response to the suction instruction.

(6) According to another aspect of the present disclosure, the controller may be configured to keep the first valve in a closed state in the valve-opening operation, after executing the valve-opening operation, the valve-closing operation, and the suction operation a certain number of times fewer than the predetermined number of times.

(7) According to another aspect of the present disclosure, the controller may be configured to execute the valve-opening operation again, after having repeatedly executed the valve-opening operation, the valve-closing operation, and the suction operation the predetermined number of times.

(8) According to another aspect of the present disclosure, the suction device may suck each of the first liquid and the second liquid as much as a predetermined amount by being driven for the predetermined time period, and the predetermined amount is larger than a volume of the first tank and a volume of the second tank.

(9) According to another aspect of the present disclosure, the controller may be configured to: execute a recording operation of discharging the first liquid and the second liquid from the head, in a state that the first valve and the second valve are closed; execute a first valve opening and closing operation of opening the first valve depending on output of a third signal from the first sensor, and closing the first valve depending on output of the first signal from the first sensor after the outputting of the third signal, the third signal being a signal indicating that the amount of the first liquid in the first tank is less than a third threshold value smaller than the first threshold value; execute a second valve opening and closing operation of opening the second valve depending on output of a fourth signal from the second sensor, and closing the second valve depending on output of the second signal from the second sensor after the outputting of the fourth signal, the fourth signal being a signal indicating that the amount of the second liquid in the second tank is less than a fourth threshold value smaller than the second threshold value; and stop the first valve opening and closing operation and the second valve opening and closing operation in response to the receiving of the suction instruction until completion of the executing of the suction operation.

(10) According to another aspect of the present disclosure, the first sensor may include a first signal outputting sensor configured to output the first signal and a third signal outputting sensor configured to output the third signal, and the second sensor may include a second signal outputting sensor configured to output the second signal and a fourth signal outputting sensor configured to output the fourth signal.

(11) An image recording device according to another aspect of the present disclosure includes: the liquid supply device as described in any one of (1) to (10); and a conveyer configured to convey a recording medium to which the first liquid and the second liquid are to be discharged from the head.

(12) A method of supplying liquid according to another aspect of the present disclosure is a method of supplying liquid using a first reservoir configured to store a first liquid; a second reservoir configured to store a second liquid; a first

tank which has a flexibility and which is positioned lower than the first reservoir; a second tank which has a flexibility and which is positioned lower than the second reservoir; and a head, the first liquid being capable of flowing into the head from the first tank through a first channel, the second liquid being capable of flowing into the head from the second tank through a second channel.

The method includes:

opening a first valve configured to open and close a channel connecting the first reservoir and first tank, and opening a second valve configured to open and close a channel connecting the second reservoir and the second tank, in response to receiving of a suction instruction; after the opening of the first valve and the second valve, closing the first valve depending on output of a first signal from a first sensor, and closing the second valve depending on output of a second signal from a second sensor, the first signal being a signal indicating that an amount of the first liquid in the first tank is a first threshold value or more, the second signal being a signal indicating that an amount of the second liquid in the second tank is a second threshold value or more; and

after the closing of the first valve and the second valve, driving a suction mechanism for a predetermined time period, the suction mechanism being configured to drive so that a suction pressure is applied to the first channel and the second channel from a head side, of the first channel and the second channel, at which the head is positioned.

The present disclosure results in difference in liquid amounts flowing into a head through a plurality of channels by suction becoming smaller.

FIG. 1 is a schematic view depicting internal configuration of a printer 10.

FIG. 2 is a diagram depicting a moving range of a carriage 41.

FIG. 3 is a block diagram depicting configuration of a controller 60 and elements connected to the controller 60.

FIG. 4 is a schematic view depicting configuration of an ink supply unit 50.

FIGS. 5A and 5B are diagrams each depicting configuration of a head 42 and its periphery. FIG. 5A is a perspective view of the head 42 and its periphery. FIG. 5B is a cross-sectional view of an exhaust portion 45.

FIG. 6 is a flowchart of ink automatic supply processing by the controller 60.

FIG. 7 is a flowchart of image recording processing by the controller 60.

FIG. 8 is a flowchart of initial introduction processing by the controller 60.

FIG. 9 is a flowchart of initial introduction processing by a controller 60.

A printer 10 (one example of an image recording device) and ink supply unit 50 (one example of a liquid supply device) according to an embodiment of the present disclosure will be described below. Note that the embodiment described below is merely one example of the present disclosure, and it goes without saying that the embodiment of the present disclosure can be appropriately altered in a range not altering the gist of the present disclosure. In the description below, progression from a start point to an end point of an arrow will be expressed as orientation, and coming and going on a line connecting a start point and an end point of an arrow will be expressed as direction. Moreover, an up-down direction 7 is defined with reference to a state of the printer 10 having been useably installed (the

state of FIG. 1), a front-rear direction **8** is defined assuming a surface provided with a discharge port **13** to be a front surface, and a left-right direction **9** is defined looking at the printer **10** from the front. The up-down direction **7**, the front-rear direction **8**, and the left-right direction **9** are orthogonal to each other.

[Overall Configuration of Printer 10]

The printer **10** depicted in FIG. 1 is an image recording device that records an image on a sheet **S** (one example of a recording medium) by an ink jet recording system. The sheet **S** is a long paper sheet that has been wound into a roll shape. In order for the sheet **S** to be mounted in the printer **10**, a winding center of the sheet **S** has a through-hole formed therein. A recording objective medium may be the likes of a seal paper, fan-fold paper, cut paper, or a fabric.

The printer **10** comprises a housing **11** of substantially rectangular parallelepiped shape. The housing **11** has a size enabling it to be mounted on a tabletop, on a floor, or in a rack, and so on. Located in a front wall **12** of the housing **11** is the discharge port **13** which is slit-like and extends in the left-right direction **9**. The sheet **S** that has been recorded with an image by the printer **10** is discharged from the discharge port **13**. The discharged sheet **S** is wound by a winding device (not depicted) fitted to the printer **10**, for example.

As depicted in FIG. 1, the printer **10** comprises the following within the housing **11**, namely, a holder **21**, a tensioner **22**, a conveying roller pair **23**, a discharging roller pair **24**, a platen **25**, a cartridge holder **26**, a carriage **41**, a head **42**, and the ink supply unit **50** (see FIG. 4). The head **42** is installed in the carriage **41**. The cartridge holder **26** is fitted with a cartridge **51** that stores ink (one example of a liquid). As depicted in FIG. 2, the printer **10** further comprises the following within the housing **11**, namely, two guide rails **37**, **38** and a cap **81**. As depicted in FIG. 3, the printer **10** further comprises the following within the housing **11**, namely, a controller **60**, a motor for holder drive **71**, a motor for conveyance **72**, a motor for carriage drive **73**, and a motor for cap drive **74**. The printer **10** may further comprise a wipe unit, various kinds of motors, various kinds of sensors, and so on, besides the above-mentioned elements.

[Conveying Mechanism of Sheet S]

Located inside the housing **11** are a pair of side frames (not depicted) that extend in the up-down direction **7** and the front-rear direction **8**. The holder **21** has a rotating shaft **31** that supports the sheet **S**. The rotating shaft **31** extends in the left-right direction **9** and has its two ends fixed to the side frames. Motive power of the motor for holder drive **71** (see FIG. 3) is transmitted to the rotating shaft **31**. This motive power causes the holder **21** to rotate in a circumferential direction of the rotating shaft **31**. In FIG. 1, a rotating direction of the holder **21** is counter-clockwise. Rotation of the holder **21** causes a roll body supported by the holder **21** to rotate too. The sheet **S** is led out upwardly from a rear end of the roll body and guided to the tensioner **22** as a result of the conveying roller pair **23** and discharge roller pair **24** rotating.

The tensioner **22**, the conveying roller pair **23**, and the discharge roller pair **24** each extend in the left-right direction **9** between the side frames and are installed in a manner enabling them to rotate in a circumferential direction of their rotational axes parallel to the left-right direction **9**. The tensioner **22** is applied with a biasing force in a rearward orientation by a biasing member such as a spring. The tensioner **22** abuts on the sheet **S** led out from the roll body and thereby guides the sheet **S** in such a manner that the sheet **S** curves frontwards.

The conveying roller pair **23** include a drive roller **32** and a pinch roller **33**, and are located forward of the tensioner **22**. The discharge roller pair **24** include a drive roller **34** and a pinch roller **35**, and are located further forward than the conveying roller pair **23**. Lower end positions of the drive rollers **32**, **34** substantially coincide with an upper end position of the tensioner **22** in the up-down direction **7**. The pinch roller **33** abuts from below on the drive roller **32**. The pinch roller **35** abuts from below on the drive roller **34**.

10 Motive power of the motor for conveyance **72** (see FIG. 3) is transmitted to the drive rollers **32**, **34**. This motive power causes the drive rollers **32**, **34** to rotate. As a result, the drive rollers **32**, **34** convey the sheet **S** in a conveying orientation **6** while nipping the sheet **S** between the drive roller **32** and the pinch roller **33** as well as between the drive roller **34** and the pinch roller **35**. In the present embodiment, the conveying orientation **6** is a frontward orientation. The motor for conveyance **72**, the conveying roller pair **23**, and the discharge roller pair **24** function as a conveyer (conveying unit) that conveys the sheet **S** to which ink discharged from the head **42** lands.

[Platen 25]

25 The platen **25** is fitted to the side frames at a position between the conveying roller pair **23** and discharge roller pair **24** in the front-rear direction **8**. The platen **25** extends in the left-right direction **9** between the side frames, and includes a supporting surface **36** for the sheet **S**, that extends in the front-rear direction **8** and the left-right direction **9**. The supporting surface **36** is an upper end surface of the platen **25**. A position in the up-down direction **7** of the supporting surface **36** substantially coincides with the upper end position of the tensioner **22**. The platen **25** may be a sucking platen that sucks the sheet **S** onto the supporting surface **36**.

[Carriage 41 and Head 42]

30 As depicted in FIG. 2, the guide rails **37**, **38** extend in the left-right direction **9** parallelly to each other. Positions in the up-down direction **7** of the guide rails **37**, **38** are the same. The guide rail **38** is located rearward of the guide rail **37** in the front-rear direction **8**. Both ends of the guide rails **37**, **38** are fixed to the side frames. The carriage **41** is supported by the guide rails **37**, **38**. Motive power of the motor for carriage drive **73** (see FIG. 3) is transmitted to a carriage drive mechanism (not depicted). The carriage **41** moves in the left-right direction **9** due to action of the carriage drive mechanism, in a state of being supported by the guide rails **37**, **38**.

35 As depicted in FIG. 1, the head **42** is installed in the carriage **41**. A lower surface of the head **42** is referred to as a nozzle surface **43**. A plurality of nozzles **44** each configured to discharge ink is located in the nozzle surface **43**. The cartridge **51** fitted to the cartridge holder **26**, and the head **42** are connected via the ink supply unit **50** (see FIG. 4). Ink stored in the cartridge **51** is supplied to the head **42** via the ink supply unit **50**. While the carriage **41** is moving in the left-right direction **9**, ink that has been supplied to the head **42** is discharged from the nozzles **44**. As a result, image recording is performed on the sheet **S**.

[Controller 60]

40 As depicted in FIG. 3, the controller **60** has a CPU **61**, a ROM **62**, a RAM **63**, an EEPROM **64**, and an ASIC **65**. The ROM **62** stores the likes of various kinds of data required in operation of the controller **60**. The RAM **63** is a working memory of the CPU **61**. The EEPROM **64** stores the likes of a control program executed by the CPU **61**. Prior to image recording being executed by the printer **10**, the control program stored in the EEPROM **64** is copied to the RAM **63**. The CPU **61** executes the control program stored in the

RAM 63. As a result, the controller 60 executes ink automatic supply processing, image recording processing, and initial introduction processing that will be described later. The controller 60 is one example of a controller.

The controller 60 is electrically connected to the motor for holder drive 71, the motor for conveyance 72, the motor for carriage drive 73, the motor for cap drive 74, a motor for elevator member drive 75, a motor for pump drive 76, and the head 42, via the ASIC 65. The motor for holder drive 71, the motor for conveyance 72, the motor for carriage drive 73, the motor for cap drive 74, the motor for elevator member drive 75, and the motor for pump drive 76 rotate according to control from the controller 60, and generate motive power. The head 42 discharges ink onto the sheet S conveyed on the platen 25, according to control from the controller 60.

The holder 21 rotates due to motive power from the motor for holder drive 71. The drive rollers 32, 34 rotate due to motive power from the motor for conveyance 72. The sheet S is conveyed in the conveying orientation 6 due to motive power from the motor for conveyance 72. The carriage 41 moves in the left-right direction 9 due to motive power from the motor for carriage drive 73. The cap 81 moves in the up-down direction 7 between a relatively high covering position and a relatively low separated position, due to motive power from the motor for cap drive 74. An elevator member 106 (see FIG. 5B; details described later) moves in the up-down direction 7 between a relatively high abutting position and a relatively low non-abutting position, due to motive power from the motor for elevator member drive 75. A pump 85 (see FIG. 4), which is driven by motive power from the motor for pump drive 76, provides a suction pressure to a channel connected to the pump 85. Note that some of the motor for holder drive 71, the motor for conveyance 72, the motor for carriage drive 73, the motor for cap drive 74, the motor for elevator member drive 75, and the motor for pump drive 76 may be realized by a common motor.

[Moving Range of Carriage 41, and Cap 81]

As depicted in FIG. 2, the platen 25, which has a shape long in the left-right direction 9, is located below the carriage 41 in the up-down direction 7 (see FIG. 1). A left end of the platen 25 is located close to left ends of the guide rails 37, 38 in the left-right direction 9. A right end of the platen 25 is located further to the right than centers of the guide rails 37, 38 in the left-right direction 9. The cap 81 is located to the right of the platen 25 in the left-right direction 9. While image recording is being executed by the printer 10, the carriage 41 moves in the left-right direction 9 within a range of the platen 25. While image recording is not being executed by the printer 10, the carriage 41 is located in a position where the head 42 faces the cap 81 (hereafter, referred to as a standby position).

As depicted in FIG. 4, the cap 81 includes: a nozzle cap 82 configured to cover the nozzle surface 43 of the head 42; and an exhaust cap 83 configured to cover an exhaust port surface 46 of an exhaust portion 45 (details of which will be described later). When the carriage 41 is located in the standby position, the cap 81 is located in the covering position. At this time, the nozzle cap 82 covers the nozzle surface 43 of the head 42, and the exhaust cap 83 covers the exhaust port surface 46 of the exhaust portion 45. When the carriage 41 is located in a position other than the standby position, the cap 81 is located in the separated position. At this time, the nozzle cap 82 does not cover the nozzle surface 43, and the exhaust cap 83 does not cover the exhaust port surface 46. In this way, the cap 81 has a function of covering

the nozzle surface 43 and the exhaust port surface 46 in a time period in which image recording is not executed. [Ink Supply Unit 50]

The ink supply unit 50 of the printer 10 will be described with reference to FIG. 4. The cartridge holder 26 (see FIG. 1) is installed with four cartridges 51b, 51c, 51m, 51y that respectively store black, cyan, magenta, and yellow inks. The ink supply unit 50 comprises the cartridges 51b, 51c, 51m, 51y, four valves 52b, 52c, 52m, 52y, four sub-tanks 53b, 53c, 53m, 53y, eight sensors 54b, 54c, 54m, 54y, 55b, 55c, 55m, 55y, the head 42, the pump 85, and the controller 60.

The inks stored in the cartridges 51b, 51c, 51m, 51y, which are so-called latex inks, contain a pigment, resin fine particles, and an additive. The ink has a viscosity suitable for evenly dispersing the pigment and the resin fine particles. The pigment represents the color of the ink. The resin fine particles, which are for causing the pigment to adhere to the sheet S, are of a synthetic resin whose glass transition temperature is exceeded by heating of a heater (not depicted), for example. Note that the printer 10 may be installable with at least two cartridges, and may have at least two sub-tanks.

An ink channel 56b connects the cartridge 51b and the sub-tank 53b. An ink channel 56c connects the cartridge 51c and the sub-tank 53c. An ink channel 56m connects the cartridge 51m and the sub-tank 53m. An ink channel 56y connects the cartridge 51y and the sub-tank 53y. An ink channel 57b connects the sub-tank 53b and the head 42. An ink channel 57c connects the sub-tank 53c and the head 42. An ink channel 57m connects the sub-tank 53m and the head 42. An ink channel 57y connects the sub-tank 53y and the head 42.

The ink stored in the cartridge 51b is supplied to the sub-tank 53b via the ink channel 56b. The sub-tank 53b stores the ink that has been supplied from the cartridge 51b. The ink stored in the sub-tank 53b is supplied to the head 42 via the ink channel 57b. Similarly, the ink stored in the cartridge 51c is supplied to the head 42 via the ink channel 56c, the sub-tank 53c, and the ink channel 57c. The ink stored in the cartridge 51m is supplied to the head 42 via the ink channel 56m, the sub-tank 53m, and the ink channel 57m. The ink stored in the cartridge 51y is supplied to the head 42 via the ink channel 56y, the sub-tank 53y, and the ink channel 57y.

The sub-tanks 53b, 53c, 53m, 53y are flexible. Outer shapes of the sub-tanks 53b, 53c, 53m, 53y change between an expanded (swollen) state and a contracted (shrunken) state depending on an amount of ink stored therein. The sub-tank 53b is located in a lower position than the cartridge 51b. Supply of ink from the cartridge 51b to the sub-tank 53b is performed by water head difference. Supply of ink from the sub-tank 53b to the head 42 is initially performed by sucking the ink from the head 42 side by the pump 85. Subsequently, the same amount of ink as ink that has been discharged from the head 42 is supplied to the head 42 from the sub-tank 53b. Supply of ink from the sub-tanks 53c, 53m, 53y to the head 42 is performed by a similar method too.

The black ink can flow into the head 42 through the ink channel 57b from the sub-tank 53b, the cyan ink can flow into the head 42 through the ink channel 57c from the sub-tank 53c, the magenta ink can flow into the head 42 through the ink channel 57m from the sub-tank 53m, and the yellow ink can flow into the head 42 through the ink channel 57y from the sub-tank 53y. The ink supply unit 50 has four ink channels (an ink channel for black ink, an ink channel for

cyan ink, an ink channel for magenta ink, and an ink channel for yellow ink) between the cartridges **51b**, **51c**, **51m**, **51y** and the head **42**.

The sensors **54b**, **55b**, which are located on an inside or an outside of the sub-tank **53b**, detect ink amount of the sub-tank **53b**. The sensor **54b** outputs a sensor signal **Sb1** indicating that ink amount of the sub-tank **53b** (amount of the ink in the sub-tank **53b**) is a threshold value **TH1** or more. The sensor **55b** outputs a sensor signal **Sb2** indicating that ink amount of the sub-tank **53b** is less than a threshold value **TH2**. Similarly, the sensors **54c**, **54m**, **54y** respectively output sensor signals **Sc1**, **Sm1**, **Sy1** indicating that ink amounts of the sub-tanks **53c**, **53m**, **53y** are the threshold values **TH1** or more. The sensors **55c**, **55m**, **55y** respectively output sensor signals **Sc2**, **Sm2**, **Sy2** indicating that ink amounts of the sub-tanks **53c**, **53m**, **53y** are less than the threshold values **TH2**.

Each of sensors **54b**, **54c**, **54m**, **54y**, **55b**, **55c**, **55m**, **55y** detects ink amount of one of sub-tanks **53b**, **53c**, **53m**, **53y** corresponding thereto by an arbitrary method. Each sensor may detect ink amount of the one of the sub-tanks **53b**, **53c**, **53m**, **53y** corresponding thereto by optically detecting change in outer shape of the one of the sub-tanks **53b**, **53c**, **53m**, **53y** corresponding thereto, for example. Each sensor may detect ink amount of the one of the sub-tanks **53b**, **53c**, **53m**, **53y** corresponding thereto by a publicly known float system, prism system, or electrode system. The threshold values **TH2** employed in comparison with ink amounts by the sensors **55b**, **55c**, **55m**, **55y** are respectively smaller than the threshold values **TH1** employed in comparison with ink amounts by the sensors **54b**, **54c**, **54m**, **54y**. The threshold values employed in comparison with ink amounts by the sensors **54b**, **54c**, **54m**, **54y** are not necessarily all the same value, and there may be threshold value(s) whose value(s) is different from a value of the other threshold value of the four threshold values. The threshold values employed in comparison with ink amounts by the sensors **55b**, **55c**, **55m**, **55y** are not necessarily all the same value, and there may be threshold value(s) whose value(s) is different from a value of the other threshold value of the four threshold values.

The controller **60** is inputted with the sensor signals **Sb1**, **Sc1**, **Sm1**, **Sy1**, **Sb2**, **Sc2**, **Sm2**, **Sy2** that have been respectively outputted from the sensors **54b**, **54c**, **54m**, **54y**, **55b**, **55c**, **55m**, **55y**. The controller **60** outputs a control signal **Vb** of the valve **52b**, a control signal **Vc** of the valve **52c**, a control signal **Vm** of the valve **52m**, and a control signal **Vy** of the valve **52y**, based on the sensor signals the controller has been inputted with. The control signals **Vb**, **Vc**, **Vm**, **Vy** are binary signals for switching states of the valves **52** between an open state and a closed state.

The valve **52b**, which is located on the ink channel **56b**, opens and closes the ink channel **56b** according to the control signal **Vb**. The valve **52c**, which is located on the ink channel **56c**, opens and closes the ink channel **56c** according to the control signal **Vc**. The valve **52m**, which is located on the ink channel **56m**, opens and closes the ink channel **56m** according to the control signal **Vm**. The valve **52y**, which is located on the ink channel **56y**, opens and closes the ink channel **56y** according to the control signal **Vy**.

The ink channel **57b** branches on its head **42** side into a portion reaching the nozzle **44** of the head **42** and portion reaching an exhaust port **47** of the exhaust portion **45**. An inner space of the nozzle cap **82** is connected to a first end of a switching portion **84**. An inner space of the exhaust cap **83** is connected to a second end of the switching portion **84**. A third end of the switching portion **84** is connected to one end of the pump **85**. A waste liquid tank **86** is located on the

other end side of the pump **85**. The switching portion **84** switches which of the inner space of the nozzle cap **82** and inner space of the exhaust cap **83** the pump **85** is to be connected to, by control from the controller **60**. The pump **85** is one example of a suction mechanism applying a suction pressure to the ink channels **57c**, **57b**, **57m**, **57y** from the head **42** side.

[Exhaust Portion 45]

As depicted in FIG. 5A, a buffer **91** having an inner space (not depicted) configured to store a small amount of ink, is located in an upper portion of the head **42**. The buffer **91** and the head **42** are connected by a coupling portion **92** extending in the up-down direction **7**. The exhaust portion **45**, which is of rectangular parallelepiped shape, is located on a right side of the buffer **91**. The exhaust port surface **46**, which is a lower surface of the exhaust portion **45**, is located in a higher position than the nozzle surface **43** in the up-down direction **7**. Four exhaust ports **47** are located in the exhaust port surface **46**. The four exhaust ports **47** are aligned at a predetermined interval in the front-rear direction **8**.

Four ink inflow ports **93** are located in an upper surface of the buffer **91**. The four ink inflow ports **93** are respectively connected to ink tubes (not depicted) configuring parts of the ink channels **57b**, **57c**, **57m**, **57y**. Four coupling channels **94** are located in a rear portion of the coupling portion **92**. The four coupling channels **94** extend in the up-down direction **7** and are aligned in the left-right direction **9**. Four connecting portions **95** are located in an upper portion of the exhaust portion **45**. The four ink inflow ports **93** are respectively connected to the four coupling channels **94** via four ink channels (not depicted) in the buffer **91**. Ink that has reached the ink inflow port **93** passes along the ink channels in the buffer **91** and coupling channels **94** to reach the head **42** and be discharged in a downward orientation from the nozzles **44** located in the nozzle surface **43**.

The four coupling channels **94** are respectively connected to the four connecting portions **95** too, via another four ink channels (not depicted) in the buffer **91**. The four connecting portions **95** are respectively connected to the four exhaust ports **47** via four channels along which mainly gas flows. As depicted in FIG. 5B, the channel connecting the connecting portion **95** and the exhaust port **47** has a diameter enlarged portion **101**. A spring **102** and valve body **103** are located in an inner space of the diameter enlarged portion **101**. The valve body **103** has a main body portion **104** and a projecting portion **105**. The main body portion **104**, which has an outer diameter substantially equal to an inner diameter of the diameter enlarged portion **101**, is located within the diameter enlarged portion **101**. The projecting portion **105**, which has an outer diameter smaller than the inner diameter of the diameter enlarged portion **101**, projects downwardly toward the exhaust port **47** from the diameter enlarged portion **101**. The spring **102**, which is located above the valve body **103**, biases the valve body **103** in a downward orientation. In a normal state, the main body portion **104** is pressed onto a bottom surface of the diameter enlarged portion **101** by action of the spring **102**, and the four exhaust ports **47** are in a closed state.

Located below the exhaust cap **83** is the elevator member **106**. The elevator member **106** has four abutting portions **107**. The four abutting portions **107**, which have shapes projecting in an upward orientation, are aligned at a predetermined interval in the front-rear direction **8**. Four through-holes are located in a bottom surface of the exhaust cap **83**. The four through-holes are aligned at a predetermined interval in the front-rear direction **8**. The interval of the four

11

exhaust ports 47, the interval of the four abutting portions 107, and the interval of the four through-holes of the exhaust cap 83 are all the same. The four abutting portions 107 respectively penetrate the four through-holes of the exhaust cap 83.

As described above, the elevator member 106 is capable of moving in the up-down direction 7 between the relatively high abutting position and the relatively low non-abutting position, due to motive power from the motor for elevator member drive 75. The elevator member 106 is capable of moving in the up-down direction 7, independently of the exhaust cap 83. When the carriage 41 is located in the standby position and the elevator member 106 is located in the abutting position, the four abutting portions 107 respectively abut on the four projecting portions 105. At this time, the four valve bodies 103 move in an upward orientation against a restoring force of the spring 102, and separate from the bottom surface of the diameter enlarged portion 101. Hence, the four exhaust ports 47 attain an open state.

When the carriage 41 is located in the standby position and the elevator member 106 is located in the non-abutting position, the exhaust ports 47 attain a closed state. By the inner space of the nozzle cap 82 and the pump 85 being connected by the switching portion 84, and the pump 85 thereupon being driven under such condition, the ink channels 57b, 57c, 57m, 57y are provided with a suction pressure from the head 42 side. As a result, ink and gas in the ink channels 57b, 57c, 57m, 57y is discharged from the nozzles 44. The ink that has been discharged from the nozzles 44 is stored in the waste liquid tank 86.

When the carriage 41 is located in the standby position and the elevator member 106 is located in the abutting position, the exhaust ports 47 attain an open state. By the inner space of the exhaust cap 83 and the pump 85 being connected by the switching portion 84, and the pump 85 thereupon being driven under such condition, the ink channels 57b, 57c, 57m, 57y are provided with a suction pressure from the head 42 side (specifically, from the exhaust portion 54). As a result, ink and gas in the ink channels 57b, 57c, 57m, 57y is discharged from the discharge ports 47. Mainly gas is discharged from the discharge ports 47. In an aspect of the present disclosure, "applying a suction pressure to channel(s) from a head side" includes applying the suction pressure to the channel(s) by using element(s) configured to apply the suction pressure to the channel(s) from a side, of the channel(s), at which the head 42 is connected to the channel(s). Such element includes, for example, the head 42, the exhaust portion 45 and the like.

[Operation of Controller 60]

The controller 60 continuously or always executes the ink automatic supply processing depicted in FIG. 6. The controller 60 executes the initial introduction processing depicted in FIG. 8 during initial setting of the printer 10. The controller 60 executes the image recording processing depicted in FIG. 7 after initial setting of the printer 10 has been completed. The controller 60 executes image recording processing and ink automatic supply processing in parallel (or time divisionally). The controller 60 stops ink automatic supply processing while initial introduction processing is being executed.

[Ink Automatic Supply Processing]

The controller 60 repeatedly executes steps S11-S26 in the ink automatic supply processing depicted in FIG. 6. The controller 60 determines whether the sensor signal Sb2 (the signal indicating that ink amount of the sub-tank 53b is less than the threshold value TH2) has been received from the sensor 55b (step S11). In response to having determined the

12

sensor signal Sb2 to have been received (step S11: Yes), the controller 60 opens the valve 52b (step S12). Next, the controller 60 determines whether the sensor signal Sb1 (the signal indicating that ink amount of the sub-tank 53b is the threshold value TH1 or more) has been received from the sensor 54b (step S13). In response to having determined the sensor signal Sb1 to have been received (step S13: Yes), the controller 60 closes the valve 52b (step S14).

Next, the controller 60 determines whether the sensor signal Sc2 (the signal indicating that ink amount of the sub-tank 53c is less than the threshold value TH2) has been received from the sensor 55c (step S15). In response to having determined the sensor signal Sc2 to have been received (step S15: Yes), the controller 60 opens the valve 52c (step S16). Next, the controller 60 determines whether the sensor signal Sc1 (the signal indicating that ink amount of the sub-tank 53c is the threshold value TH1 or more) has been received from the sensor 54c (step S17). In response to having determined the sensor signal Sc1 to have been received (step S17: Yes), the controller 60 closes the valve 52c (step S18).

Next, the controller 60 determines whether the sensor signal Sm2 (the signal indicating that ink amount of the sub-tank 53m is less than the threshold value TH2) has been received from the sensor 55m (step S19). In response to having determined the sensor signal Sm2 to have been received (step S19: Yes), the controller 60 opens the valve 52m (step S20). Next, the controller 60 determines whether the sensor signal Sm1 (the signal indicating that ink amount of the sub-tank 53m is the threshold value TH1 or more) has been received from the sensor 54m (step S21). In response to having determined the sensor signal Sm1 to have been received (step S21: Yes), the controller 60 closes the valve 52m (step S22).

Next, the controller 60 determines whether the sensor signal Sy2 (the signal indicating that ink amount of the sub-tank 53y is less than the threshold value TH2) has been received from the sensor 55y (step S23). In response to having determined the sensor signal Sy2 to have been received (step S23: Yes), the controller 60 opens the valve 52y (step S24). Next, the controller 60 determines whether the sensor signal Sy1 (the signal indicating that ink amount of the sub-tank 53y is the threshold value TH1 or more) has been received from the sensor 54y (step S25). In response to having determined the sensor signal Sy1 to have been received (step S25: Yes), the controller 60 closes the valve 52y (step S26).

[Image Recording Processing]

The controller 60 repeatedly executes steps S31-S41 in the image recording processing depicted in FIG. 7. At a timepoint of the controller 60 executing the step S31, the carriage 41 is located in the standby position, and the cap 81 is located in the covering position. The nozzle surface 43 of the head 42 is covered by the nozzle cap 82.

The controller 60 receives an image recording instruction from an operating unit (not depicted) (step S31). Specifically, the controller 60 waits in the step S31 until it receives the image recording instruction. Upon receiving the image recording instruction in the step S31, the controller 60 closes the four valves 52b, 52c, 52m, 52y (step S32). Next, the controller 60 moves the cap 81 in a downward orientation from the covering position to the separated position (step S33).

Next, the controller 60 moves the carriage 41 in a leftward orientation to a recording start position (step S34). The recording start position is a predetermined position that the carriage 41 faces the platen 25. Next, the controller 60

conveys the sheet S to the recording start position (step S35). Note that the controller 60 may execute a step S35 in parallel with the steps S32-S34. At a timepoint of the controller 60 having completed processing up to the step S35, the printer 10 is in a state where image recording can be started.

Next, the controller 60 executes a predetermined amount of image recording on the sheet S (step S36). Specifically, the controller 60 moves the carriage 41 in the left-right direction 9. While the carriage 41 is moving in the left-right direction 9, the controller 60 causes ink corresponding to image data to be discharged from the nozzles 44 of the head 42. The step S36 is one example of a recording operation.

Next, the controller 60 determines whether there is image data remaining (step S37). In response to having determined there to be image data remaining in the step S37 (step S37: Yes), the controller 60 proceeds to a step S38. In this case, the controller 60 conveys the sheet S the predetermined amount (step S38), and proceeds to the step S36.

In response to having determined there to be no image data remaining in the step S37 (step S37: No), the controller 60 proceeds to a step S39. In this case, the controller 60 discharges the sheet S to a predetermined position (step S39). Next, the controller 60 moves the carriage 41 in a rightward orientation to the standby position (step S40). Next, the controller 60 moves the cap 81 in an upward orientation from the separated position to the covering position (step S41). After that, the controller 60 proceeds to the step S31 in order to execute the next image recording. [Initial Introduction Processing]

At a timepoint of the printer 10 having been shipped from a factory, ink does not exist in the ink channels 56b, 56c, 56m, 56y, 57b, 57c, 57m, 57y. Accordingly, after the printer 10 has been set in place and the cartridge holder 26 installed with the cartridges 51b, 51c, 51m, 51y, the controller 60 executes the initial introduction processing depicted in FIG. 8. The initial introduction processing is a processing by which the four colors of inks are introduced into the head 42 from the cartridges 51b, 51c, 51m, 51y. At a timepoint of the controller 60 executing a step S51, the carriage 41 is located in the standby position, and the cap 81 is located in the covering position. The valves 52b, 52c, 52m, 52y are closed, and the sub-tanks 53b, 53c, 53m, 53y are empty.

After the cartridge holder 26 has been installed with the cartridges 51b, 51c, 51m, 51y, the controller 60 receives an initial introduction instruction from the operating unit (step S51). Specifically, the controller 60 waits in the step S51 until it receives the initial introduction instruction. Next, the controller 60 stops the ink automatic supply processing (step S52). While executing from a step S53 to a step S60, the controller 60 does not execute the ink automatic supply processing depicted in FIG. 6. Next, the controller 60 initializes to 1 a count value N for counting number-of-times-of-suction (step S53).

Next, the controller 60 opens the four valves 52b, 52c, 52m, 52y (step S54). Thereafter, black ink is supplied from the cartridge 51b to the sub-tank 53b, cyan ink is supplied from the cartridge 51c to the sub-tank 53c, magenta ink is supplied from the cartridge 51m to the sub-tank 53m, and yellow ink is supplied from the cartridge 51y to the sub-tank 53y. Supply of these inks is performed using water head difference.

Next, the controller 60 waits until ink amounts of the four sub-tanks 53b, 53c, 53m, 53y all become the threshold values TH1 or more (step S55). Specifically, the controller 60 waits in the step S55 until the controller 60 respectively receives the sensor signals Sb1, Sc1, Sm1, Sy1 from the sensors 54b, 54c, 54m, 54y.

Next, the controller 60 closes the four valves 52b, 52c, 52m, 52y (step S56). Thereafter, supply of black ink from the cartridge 51b to the sub-tank 53b, supply of cyan ink from the cartridge 51c to the sub-tank 53c, supply of magenta ink from the cartridge 51m to the sub-tank 53m, and supply of yellow ink from the cartridge 51y to the sub-tank 53y stop.

Next, the controller 60 performs suction by driving the pump 85 for a predetermined time (step S57). While the controller 60 is executing the step S57, the valves 52b, 52c, 52m, 52y are in a closed state. The elevator member 106 (see FIGS. 5A and 5B) is located in the abutting position, and the switching portion 84 (see FIG. 4) connects the pump 85 to the inner space of the exhaust cap 83. Therefore, the ink channels 57b, 57c, 57m, 57y are provided with a suction pressure from the head 42 side (specifically, from the exhaust portion 45; that is from a side, of the ink channels 57b, 57c, 57m, 57y, at which the head 42 is connected to the ink channels 57b, 57c, 57m, 57y), and the inks that have been stored in the sub-tanks 53b, 53c, 53m, 53y are respectively introduced into the ink channels 57b, 57c, 57m, 57y. Note that the switching portion 84 (see FIG. 4) may connect the pump 85 to the inner space of the nozzle cap 82 so that the inks in the sub-tanks 53b, 53c, 53m, 53y are respectively introduced into the ink channels 57b, 57c, 57m, 57y by a suction pressure provided via the head 42. Further, the switching portion 84 may firstly connect the pump 85 to the inner space of the exhaust cap 83 for performing suction of the inks via the exhaust portion 45. And then, after performing the suction via the exhaust portion 45 several times, the elevator portion 106 is lowered to the non-abutting position and the switching portion 84 may connect the pump 85 to the inner space of the nozzle cap 82 for performing additional or finishing suction of the inks via the nozzle 44 of the head 42.

The pump 85 sucks a predetermined amount (that is, for example, a design value planned suction amount, each of which may be decided depending on a driving duration of the pump 85, a viscosity of the ink, and the like) of ink by being driven for a predetermined time period. The predetermined amount is larger than volumes (capacities) of the sub-tanks 53b, 53c, 53m, 53y (each of which may be, for example, the difference between a volume in the expanded state and a volume in the contracted state), but smaller than volumes of the ink channels 57b, 57c, 57m, 57y. Specifically, the longer a moving distance in the left-right direction 9 of the carriage 41 is (in other words, the longer the width of the sheet S is), the longer lengths of the ink channels 57b, 57c, 57m, 57y will become. Thus, the predetermined amount sucked by the pump 85 will become smaller compared to volumes of the ink channels 57b, 57c, 57m, 57y more sufficiently. Therefore, the inks of each color that have been introduced into the ink channels 57b, 57c, 57m, 57y will not reach the head 42 simply by the step S57 having been executed once by the controller 60. Accordingly, the controller 60 repeatedly executes the steps S54-S57 a predetermined number-of-times-of-suctions (hereafter, referred to as M), as described below.

Next, the controller 60 determines whether the count value N is the predetermined number-of-times-of-suctions M or more (step S58). In response to having determined the count value N is less than the number-of-times-of-suctions M in the step S58 (S58: No), the controller 60 proceeds to a step S59. In this case, the controller 60 adds 1 to the count value N (step S59), and proceeds to the step S54 in order to execute the steps S54-S57 again.

In response to having determined the count value N is the number-of-times-of-suctions M or more in the step S58 (S58: Yes), the controller 60 proceeds to a step S60. In this

case, the controller **60** opens the four valves **52b**, **52c**, **52m**, **52y** (step **S60**). Next, the controller **60** resumes ink automatic supply that has been stopped in the step **S52** (step **S61**), and finishes the initial introduction processing.

The number-of-times-of-suctions M in the step **S58** is determined such that the following expressions (1) and (2) are satisfied, for example.

$$M > Q/v \quad (1)$$

$$\beta \times (m-1) \times V < v < \alpha \times m \times V \quad (2)$$

This is provided that, in expressions (1) and (2), Q is suction amount required during initial introduction, v is suction amount (total of suction amounts in all of the ink channels) when the pump **85** is driven once in the step **S57**, m is the number of ink channels in the ink supply unit **50**, V is volume of any one of the sub-tanks **53b**, **53c**, **53m**, **53y**, and α and β indicate safety factors. The safety factors α and β take values greater than 0, but less than 1.

When the steps **S54-S56** are initially executed by the controller **60**, inks of amounts corresponding to the threshold values $TH1$ respectively flow from the cartridges **51b**, **51c**, **51m**, **51y** into the sub-tanks **53b**, **53c**, **53m**, **53y**. Subsequently, when the step **S57** is executed for the first time by the controller **60**, amounts of inks introduced into the ink channels **57b**, **57c**, **57m**, **57y** from the sub-tanks **53b**, **53c**, **53m**, **53y** will differ depending on channel resistances of the ink channels **57b**, **57c**, **57m**, **57y**, and so on. When the steps **S54-S56** are executed a second time and thereafter by the controller **60**, inks of amounts corresponding to the amounts of inks that were introduced into the ink channels **57b**, **57c**, **57m**, **57y** from the sub-tanks **53b**, **53c**, **53m**, **53y** when the step **S57** was executed the previous time by the controller **60** will respectively flow from the cartridges **51b**, **51c**, **51m**, **51y** into the sub-tanks **53b**, **53c**, **53m**, **53y**.

In the initial introduction processing, after having supplied each of the sub-tanks **53b**, **53c**, **53m**, **53y** with inks of not less than amounts corresponding to the threshold values $TH1$, the controller **60** drives the pump **85** in a state where supply of inks to each of the sub-tanks **53b**, **53c**, **53m**, **53y** from each of the cartridges **51** has been stopped. Hence, if there is a resistance difference between the ink channels **57b**, **57c**, **57m**, **57y** and there is a difference in suction amounts between the ink channels **57b**, **57c**, **57m**, **57y**, then, after one or more of the sub-tanks **53b**, **53c**, **53m**, **53y** connected to one or more of the ink channels **57b**, **57c**, **57m**, **57y** having a small channel resistance has become empty, the suction pressure of the pump **85** will be provided to the other of the ink channels **57b**, **57c**, **57m**, **57y**. Therefore, a difference in ink amounts flowing into the head **42** through the plurality of ink channels **57b**, **57c**, **57m**, **57y** by suction becomes smaller.

Let it be assumed that in the above-described embodiment, two colors differing from each other are selected from among black, cyan, magenta, and yellow, and the first letters of the English spellings of the selected two colors are set to p and q (p and q are any of b , c , m , and y). The cartridge **51p** is one example of a first reservoir, and the cartridge **51q** is one example of a second reservoir. The valve **52p** is one example of a first valve, and the valve **52q** is one example of a second valve. The sub-tank **53p** is one example of a first tank, and the sub-tank **53q** is one example of a second tank. The sensor **54p** is one example of a first sensor and a first signal outputting sensor, and the sensor **54q** is one example of a second sensor and a second signal outputting sensor. The sensor **55p** is one example of the first sensor and a third signal outputting sensor, and the sensor **55q** is one example

of the second sensor and a fourth signal outputting sensor. The sensors **54p** and **55p** may be single (or integrated) sensor, and the sensors **54q** and **55q** may be single (or integrated) sensor. The threshold value $TH1$ relating to the sensor **54p** is one example of a first threshold value, and the threshold value $TH1$ relating to the sensor **54q** is one example of a second threshold value. The threshold value $TH2$ relating to the sensor **55p** is one example of a third threshold value, and the threshold value $TH2$ relating to the sensor **55q** is one example of a fourth threshold value. The ink channel **56p** is one example of a channel connecting the first reservoir and the first tank, and the ink channel **56q** is one example of a channel connecting the second reservoir and the second tank. The ink channel **57p** is one example of a first channel, and the ink channel **57q** is one example of a second channel.

In FIG. 6, the controller **60** opens the valve **52p** in response to receiving the sensor signal **Sp2** from the sensor **55p**, and closes the valve **52p** in response to receiving the sensor signal **Sp1** from the sensor **54p** subsequently to having received the sensor signal **Sp2**. This operation is one example of a first valve opening and closing operation. The controller **60** opens the valve **52q** in response to receiving the sensor signal **Sq2** from the sensor **55q**, and closes the valve **52q** in response to receiving the sensor signal **Sq1** from the sensor **54q** subsequently to having received the sensor signal **Sq2**. This operation is one example of a second valve opening and closing operation.

In FIG. 8, the initial introduction instruction is one example of a suction instruction, the step **S54** is one example of a valve-opening operation, the step **S56** is one example of a valve-closing operation, and the step **S57** is one example of a suction operation. In response to having received the initial introduction instruction in the step **S51**, the controller **60** executes the valve-opening operation to open the valves **52b**, **52c**, **52m**, **52y** in the step **S54**. Subsequently to having executed the valve-opening operation and in response to having received from the sensors **54b**, **54c**, **54m**, **54y** a sensor signal indicating ink amount of the sub-tanks **53b**, **53c**, **53m**, **53y** to be the threshold value $TH1$ or more, the controller **60** executes the valve-closing operation to close the valves **52b**, **52c**, **52m**, **52y**. Subsequently to having executed the valve-closing operation, the controller **60** executes the suction operation to drive the pump **85** for the predetermined time period.

Effects of Embodiments

In the printer **10** and ink supply unit **50** according to the above-described embodiment, in the case that suction is performed to introduce ink into the plurality of ink channels **56b**, **56c**, **56m**, **56y** and plurality of ink channels **57b**, **57c**, **57m**, **57y** connecting the plurality of cartridges **51** and the head **42**, the pump **85** is driven in a state where the ink of not less than a predetermined amount has been supplied to each of the sub-tanks **53b**, **53c**, **53m**, **53y** and supply of ink to each of the sub-tanks **53b**, **53c**, **53m**, **53y** from each of the cartridges **51** then has been stopped. Therefore, difference in ink amounts flowing into the head **42** through the plurality of ink channels **57b**, **57c**, **57m**, **57y** by suction becomes smaller.

The controller **60** executes the valve-opening operation after executing the suction operation. Hence, after the suction operation has been executed, ink will be supplied to each of the sub-tanks **53b**, **53c**, **53m**, **53y**. The controller **60** opens the corresponding one of the valves **52b**, **52c**, **52m**, **52y** in response to receiving from one of the sensors **55b**,

55c, 55m, 55y a sensor signal indicating ink amount of one of the sub-tanks 53b, 55c, 55m, 55y is less than the threshold value TH2. Hence, when ink amount of each of the sub-tanks 53b, 53c, 53m, 53y becomes less than a designated amount, ink will be supplied to each of the sub-tanks 53b, 53c, 53m, 53y.

In response to receiving the initial introduction instruction, the controller 60 repeatedly executes the valve-opening operation, the valve-closing operation, and the suction operation the predetermined number-of-times-of-suctions M (one example of a predetermined number of times). Hence, a required amount of ink can be introduced into each of the ink channels 57. After having repeatedly executed the valve-opening operation, the valve-closing operation, and the suction operation the number-of-times-of-suctions M, the controller 60 executes the valve-opening operation. Hence, after the valve-opening operation, the valve-closing operation, and the suction operation have been repeatedly executed, ink will be supplied to each of the sub-tanks 53.

The controller 60 executes the image recording operation in a state of the valves 52b, 52c, 52m, 52y having been closed. The controller 60 executes the first valve opening and closing operation and the second valve opening and closing operation, and, in response to receiving the initial introduction instruction, does not execute (that is, stops) the first valve opening and closing operation and the second valve opening and closing operation until execution of the suction operation has been completed. Hence, even in the case of automatic supply of inks from each of the cartridges 51 to each of the sub-tanks 53b, 53c, 53m, 53y being performed, automatic supply of the inks will be stopped and each of the valves 52b, 52c, 52m, 52y will be closed until execution of the suction operation is completed.

While the invention has been described in conjunction with various example structures outlined above and illustrated in the figures, various alternatives, modifications, variations, improvements, and/or substantial equivalents, whether known or that may be presently unforeseen, may become apparent to those having at least ordinary skill in the art. Accordingly, the example embodiments of the disclosure, as set forth above, are intended to be illustrative of the invention, and not limiting the invention. Various changes may be made without departing from the spirit and scope of the disclosure. Therefore, the disclosure is intended to embrace all known or later developed alternatives, modifications, variations, improvements, and/or substantial equivalents. Some specific examples of potential alternatives, modifications, or variations in the described invention are provided below:

Modified Example

Various kinds of modified examples may be configured for the printer 10 and controller 60 according to the above-described embodiment. In the above-described embodiment, controller 60 executes the initial introduction processing depicted in FIG. 8. In a modified example, a controller 60 executes an initial introduction processing depicted in FIG. 9.

The initial introduction processing depicted in FIG. 9 is the initial introduction processing depicted in FIG. 8 to which a step S71 and a step S74 have been added and in which the step S54 and the step S56 have been respectively replaced by a step S72 and a step S73. The controller 60 according to the modified example uses four flags Fb, Fc, Fm, Fy respectively corresponding to black, cyan, magenta, and yellow to execute the initial introduction processing.

Each of the flags Fb, Fc, Fm, Fy is cleared in a state where introduced amount of the ink of corresponding color is insufficient, and is set in a state where introduced amounts of the ink of corresponding color is sufficient. The flags Fb, Fc, Fm, Fy are stored in the RAM 63 (see FIG. 3).

After executing the step S51 and the step S52, the controller 60 clears the four flags Fb, Fc, Fm, Fy (step S71). After executing the step S53 or the step S59, the controller 60 opens valves corresponding to cleared flags, of the valves 52b, 52c, 52m, 52y (step S72). If, for example, the flags Fb, Fy are cleared and the flags Fc, Fm are set, then in the step S72, the controller 60 will open the valves 52b, 52y and leave closed the valves 52c, 52m.

After executing the step S55, the controller 60 closes valves that are open, of the valves 52b, 52c, 52m, 52y (step S73). After executing the step S57, the controller 60 sets flags of colors whose ink introduction amounts are sufficient, of the flags Fb, Fc, Fm, Fy (step S74). In the step S74, the controller 60 determines whether ink introduction amounts of each of the colors are sufficient, based on the sensor signals Sb1, Sc1, Sm1, Sy1, Sb2, Sc2, Sm2, Sy2 respectively outputted from the sensors 54b, 54c, 54m, 54y, 55b, 55c, 55m, 55y. For example, the controller 60 will set the flag Fb in response to a determination that introduction amount of black ink has become sufficient by the step S57 executed immediately priorly.

In the controller 60 according to the modified example, after executing the valve-opening operation, the valve-closing operation, and the suction operation a certain number of times which is fewer than the predetermined number-of-times-of-suctions M, the controller 60 keeps at least one of the valves 52b, 52c, 52m, 52y in a closed state in the valve-opening operation. Hence, this modified example results in that, for a channel where introduction of ink has been completed, supply of ink from the cartridge 51 to the corresponding one of the sub-tanks 53b, 53c, 53m, 53y can be stopped and needless discharge of ink thereby prevented.

In the above-described embodiment, the printer 10 is configured to comprise one head 42. However, the printer 10 may comprise two or more heads 42. In the above-described embodiment, the ink supply unit 50 of the printer 10 is configured to comprise four ink channels. However, the printer 10 may comprise two, three, or five or more ink channels.

What is claimed is:

1. A liquid supply device comprising:
a first reservoir configured to store a first liquid;
a second reservoir configured to store a second liquid;
a first tank having flexibility, the first tank being positioned lower than the first reservoir;
a second tank having a flexibility, the second tank being positioned lower than the second reservoir;
a first valve configured to open and close a channel connecting the first reservoir and the first tank;
a second valve configured to open and close a channel connecting the second reservoir and the second tank;
a head, the first liquid being capable of flowing into the head from the first tank through a first channel, the second liquid being capable of flowing into the head from the second tank through a second channel;
a suction mechanism configured to drive so that a suction pressure is applied to the first channel and the second channel from a head side, of the first channel and the second channel, at which the head is positioned;
a first sensor;
a second sensor; and
a controller, wherein

19

the controller is configured to:

execute a valve-opening operation of opening the first valve and the second valve, in response to a suction instruction;

execute, after executing the valve-opening operation, a valve-closing operation of closing the first valve depending on output of a first signal from the first sensor, and closing the second valve depending on output of a second signal from the second sensor, the first signal being a signal indicating that an amount of the first liquid in the first tank is a first threshold value or more, the second signal being a signal indicating that an amount of the second liquid in the second tank is a second threshold value or more;

execute, after executing the valve-closing operation, a suction operation of driving the suction mechanism, for a predetermined time period, so as to suck the first liquid in the first tank to the head through the first channel and suck the second liquid in the second tank to the head through the second channel, the sucking of the first liquid in the first tank and the sucking of the second liquid in the second tank being started after the closing of the first valve and the second valve;

execute a first valve opening and closing operation of opening the first valve depending on output of a third signal from the first sensor, and closing the first valve depending on output of the first signal from the first sensor after the outputting of the third signal, the third signal being a signal indicating that the amount of the first liquid in the first tank is less than the first threshold value or a signal indicating that the amount of the first liquid in the first tank is less than a third threshold value smaller than the first threshold value; and

stop the first valve opening and closing operation in response to the receiving of the suction instruction until completion of the executing of the suction operation.

2. The liquid supply device according to claim 1, wherein the controller is configured to execute, after executing the suction operation, the valve-opening operation again.

3. The liquid supply device according to claim 1, wherein the controller is configured to open the first valve depending on output of the third signal from the first sensor, and open the second valve depending on output of a fourth signal from the second sensor, the fourth signal being a signal indicating that the amount of the second liquid in the second tank is less than a fourth threshold value smaller than the second threshold value.

4. The liquid supply device according to claim 3, wherein the first sensor includes a first signal outputting sensor configured to output the first signal and a third signal outputting sensor configured to output the third signal, and the second sensor includes a second signal outputting sensor configured to output the second signal and a fourth signal outputting sensor configured to output the fourth signal.

5. The liquid supply device according to claim 2, wherein the controller is configured to repeatedly execute the valve-opening operation, the valve-closing operation, and the suction operation a predetermined number of times, in response to the suction instruction.

6. The liquid supply device according to claim 5, wherein the controller is configured to keep the first valve in a closed state in the valve-opening operation, after executing the valve-opening operation, the valve-closing operation, and

20

the suction operation a certain number of times fewer than the predetermined number of times.

7. The liquid supply device according to claim 5, wherein the controller is configured to execute the valve-opening operation again, after having repeatedly executed the valve-opening operation, the valve-closing operation, and the suction operation the predetermined number of times.

8. The liquid supply device according to claim 1, wherein the suction device sucks each of the first liquid and the second liquid as much as a predetermined amount by being driven for the predetermined time period, and the predetermined amount is larger than a volume of the first tank and a volume of the second tank.

9. The liquid supply device according to claim 1, wherein the controller is configured to:

execute a recording operation of discharging the first liquid and the second liquid from the head, in a state that the first valve and the second valve are closed; execute a second valve opening and closing operation of opening the second valve depending on output of a fourth signal from the second sensor, and closing the second valve depending on output of the second signal from the second sensor after the outputting of the fourth signal, the fourth signal being a signal indicating that the amount of the second liquid in the second tank is less than a fourth threshold value smaller than the second threshold value; and

stop the second valve opening and closing operation in response to the receiving of the suction instruction until completion of the executing of the suction operation.

10. The liquid supply device according to claim 9, wherein the first sensor includes a first signal outputting sensor configured to output the first signal and a third signal outputting sensor configured to output the third signal, and the second sensor includes a second signal outputting sensor configured to output the second signal and a fourth signal outputting sensor configured to output the fourth signal.

11. An image recording device comprising:
the liquid supply device as defined in claim 1; and
a conveyer configured to convey a recording medium to which the first liquid and the second liquid are to be discharged from the head.

12. The liquid supply device according to claim 1, wherein the third signal is the signal indicating that the amount of the first liquid in the first tank is less than the third threshold value.

13. A method of supplying liquid using a first reservoir configured to store a first liquid; a second reservoir configured to store a second liquid; a first tank which has a flexibility and which is positioned lower than the first reservoir; a second tank which has a flexibility and which is positioned lower than the second reservoir; and a head, the first liquid being capable of flowing into the head from the first tank through a first channel, the second liquid being capable of flowing into the head from the second tank through a second channel, the method comprising:

opening a first valve configured to open and close a channel connecting the first reservoir and first tank, and opening a second valve configured to open and close a channel connecting the second reservoir and the second tank, in response to receiving of a suction instruction; after the opening of the first valve and the second valve, closing the first valve depending on output of a first signal from a first sensor, and closing the second valve depending on output of a second signal from a second sensor, the first signal being a signal indicating that an amount of the first liquid in the first tank is a first

threshold value or more, the second signal being a signal indicating that an amount of the second liquid in the second tank is a second threshold value or more; after the closing of the first valve and the second valve, driving a suction mechanism for a predetermined time period, the suction mechanism being configured to drive so that a suction pressure is applied to the first channel and the second channel from a head side, of the first channel and the second channel, at which the head is positioned; 5
executing a first valve opening and closing operation of opening the first valve depending on output of a third signal from the first sensor, and closing the first valve depending on output of the first signal from the first sensor after the outputting of the third signal, the third signal being a signal indicating that the amount of the first liquid in the first tank is less than the first threshold value or a signal indicating that the amount of the first liquid in the first tank is less than a third threshold value smaller than the first threshold value; and 10
stopping the first valve opening and closing operation in response to the receiving of the suction instruction until completion of the executing of the suction operation. 15
